IGNITION CABLE

Melville F. Peters, Beltsville, Md.

Application June 19, 1936, Serial No. 86,126

2 Claims. (Cl. 173—264)

(Granted under the act of March 3, 1883, as
amended April 30, 1928; 370 O. G. 757)

This application is a continuation in part of my co-pending application Serial No. 726,895, filed May 22, 1936, now Patent No. 2,058,619.

The present invention relates to ignition cables, particularly those designed for transmitting electric energy to spark plugs or other ignition devices of internal combustion engines, and has for its object the provision of such a cable which will have a minimum capacitance and a maximum 5 inductance and resistance without subjecting the dielectric material of the cable to excessive electrical stresses, reducing the mechanical strength of the cable or causing the spark discharge to become aperiodic.

With this object in view the present invention provides an ignition cable comprising a conductor and insulating means surrounding the conductor, these parts being so designed that the ratio of the diameter of the conductor to the 10 diameter of the cable shall be such that for any fixed outside diameter of the cable and with respect to the voltage necessary to fire the plugs, the capacitance of the cable shall have the smallest value consistent with safe electrical gradient 15 in the insulator adjacent the conductor, and such ratio shall have the smallest possible value consistent with safe electrical gradient in the insulation adjacent the conductor. In so designing an ignition cable according to the invention, the mechanical strength of the cable is a further limiting factor in the reduction of the ratio of the 20 diameter of the conductor to the outside diameter of the cable and such ratio is accordingly reduced only to a value consistent with sufficient 25 mechanical strength of the conductor. Where ignition cables according to the invention are to be employed under conditions of high temperature, certain effects resulting from the use of heat-resistant insulation must often be taken into consideration, and the invention contemplates 30 the provision of an ignition cable designed to be operable and effective under such high-temperature conditions.

The invention is designed more in detail in the 35 following specification which is accompanied by a drawing in which,

Fig. 1 is a cross-sectional view of a cable which may be constructed according to the present invention;

Fig. 2 is a graphic analysis of certain features 40 of the invention, and

Fig. 3 is a schematic view of parts of an ignition system.

It is well known that the ignition system of 45 an internal combustion engine interferes consid-

erably with reception by radio receiving sets carried by vehicles which are driven by such internal combustion engines. This effect is due to the fact that the component parts of the ignition system, such as the magneto, leads and spark 5 plugs, act as condensers and the capacity effect so produced causes electrical conditions to be set up which react adversely on the signal reception of any nearby radio receiver.

In order to prevent or decrease the interference 10 with radio reception caused by ignition systems, as described hereinbefore, it has become the common practice to shield the various parts of the ignition system in various manners, as by incasing the ignition leads and spark plugs in shields 15 of metal, or other materials. When such shielding harness is employed it has been found that the capacitance to ground of the shielded ignition system is increased, thereby requiring a greater amount of energy to be supplied by the 20 spark generator to produce the required breakdown voltage at the spark plugs. While the use of shielding increases greatly the capacitance to ground of the ignition system, thereby rendering the present invention particularly valuable in 25 connection with shielded systems, the invention is also useful with unshielded systems. In ignition systems employing no shielding whatsoever, the problems and effects caused by capacitance 30 are almost as marked as those in shielded systems. In the shielded systems the shielding harness provides the ground, while in unshielded systems the engine or other metallic part is the ground. The present invention is therefore fully 35 applicable to both shielded and unshielded systems and when the capacitance of the ignition system is referred to hereinafter, it is to be understood as referring to the capacitance to ground of either a shielded or unshielded ignition system.

In this connection it has been found that the energy required to bring the secondary side of an ignition system up to the breakdown voltage of the spark-gap may be expressed by the equation

$$H = \frac{1}{2}CE^2$$

H is the energy required, expressed in jouls. C is the capacitance of the secondary side, expressed in farads, and E is the breakdown voltage of the gap expressed in volts.

It will be apparent from this equation that the energy required to bring the secondary side of the ignition system up to the breakdown voltage of the spark-gap varies directly as the capacitance of such secondary side.

45

50

55

It has further been found that in an unshielded ignition system employing the present type of ignition cable, the capacitance of each of the secondary leads is of the order of 40×10^{-12} to 5 110×10^{-12} farads. When this same cable is placed in a shielding harness the capacitance of the longest lead may be increased to 250×10^{-12} to 350×10^{-12} farads. It will be apparent, therefore, that the increased capacitance due to shielding causes a very appreciable increase in the amount of energy required from the spark generator to bring the secondary side of the ignition system up to the breakdown voltage of the spark-gap. This effect is so pronounced that it 10 has long been observed that magneto and spark coil operation in shielded systems is not as satisfactory as in unshielded harnesses.

In studying this problem, I have found that the capacitance of a shielded harness may be reduced by employing a wire in the ignition system which will have such characteristics that a maximum decrease in the capacitance of the secondary side of the ignition system is obtained because of the use of such wire. Such a wire, in order to 20 obtain the optimum results should have as low a capacitance per unit length as is consistent with a good value of electrical gradient for such wire. In other words, the wire, or ignition cable, should be so designed as to have the smallest possible 25 capacitance when placed in a metal shield without weakening the cable mechanically or subjecting the dielectric to excessive electrical stresses.

Referring to Fig. 1 of the drawing it will be seen that a cross-section of an ignition cable is 30 closed; the same comprising the wire conductor 1, the rubber insulation 2, the braid 3, the lacquer 4, and the shielding 5, all of such elements being disposed about the wire conductor in abutting concentric cylinders. It will also be observed 35 that the elements noted have, respectively, the radii r_1 , r_2 , r_3 , r_4 and r_5 . This specific cable construction is shown for purpose of illustration only, as it will be apparent that a greater or less number of dielectric and shielding materials may be 40 employed without, in any way, departing from the scope of the invention. In a cable having n layers of insulation, the outside radius of the cable will be represented by the term r_{n+1} . A schematic view of a shielded ignition system is 45 disclosed in Fig. 3, in which is disclosed the magneto 50 6, distributor 7, cable 8, spark plug 9, and shielding 10.

In developing the construction of an ignition cable having the best practical characteristics as 55 outlined above, I have considered the component members of the cable as a plurality of concentric cylinders. When an electric current is passed through the cable, the lines of force of the field set up by such current are radial, and the number 60 of lines of force touching the surface of the inner cylinder, or wire, must equal the number touching the outer cylinder. Since the flux density is equal to the total flux divided by the area, it is obvious that the flux density, and therefore, the gradient, is generally greatest at the 65 surface of the inner cylinder.

In case a homogeneous dielectric is used and the outer cylinder grounded, the capacitance per unit length may be found as follows:

If the inner cylinder is given a charge ψ per 70 unit length, the electric intensity, or gradient, g_x , at a distance x from the axis is given by text-books as

$$g_x = \frac{dV}{dx} = \frac{-2\psi}{\epsilon_x}$$

where V is the difference of potential between the wire and the point x and, since $\psi = CE$

$$g_x = \frac{-2CE}{\epsilon_x} \quad (1) \quad 5$$

in which C is the capacitance, E is the potential difference between the wire and the shield, and ϵ is the specific inductive capacitance of the dielectric.

The potential difference between the inner and outer cylinders may be obtained by integrating between the inner and outer radii i. e. 10

$$\int_0^E dV = E = \frac{-2\psi}{\epsilon} \int_{r_{n+1}}^{r_1} \frac{dx}{x} = \frac{2\psi}{\epsilon} \log \frac{r_1}{r_{n+1}} \quad (2) \quad 15$$

and, since $\psi = CE$

$$C = \frac{\epsilon}{2 \log \frac{r_1}{r_{n+1}}} \text{ centimeters per cm. of length} \quad (3) \quad 20$$

Applying the conversion factor for transforming capacitance in centimeters into capacitance in farads, this gives

$$C = \frac{10^9}{V^2} \cdot \frac{\epsilon}{2 \log \frac{r_1}{r_{n+1}}} = \frac{(5.55 \times 10^{-13})\epsilon}{\log \frac{r_1}{r_{n+1}}} \left\{ \begin{array}{l} \text{farads per} \\ \text{cm. of length} \end{array} \right\} \quad (4) \quad 25$$

Substituting Equation 3 in Equation 1 an equation for the electric gradient expressed in volts per unit of length is obtained, i. e. 30

$$\frac{dV}{dx} = g_x = \frac{-E}{x \log \frac{r_1}{r_{n+1}}} \text{ volts per centimeter}$$

The sign is negative because the inner cylinder is at a higher potential than the outer cylinder. 35 In this case, it is the absolute value of the gradient which is of importance and the equation may therefore be written

$$\frac{dV}{dx} = \frac{E}{x \log \frac{r_1}{r_{n+1}}} \quad (5) \quad 40$$

The maximum electric gradient occurs where $x = r_1$ which is the minimum value of x , or

$$g_{max} = \frac{E}{r_1 \log \frac{r_1}{r_{n+1}}} \quad (6) \quad 45$$

In case a number of dielectrics are used, as in an ignition cable, the capacitance and gradient may be determined by assuming each dielectric to 50 represent a condenser and these condensers to be connected in series. The lines of force of flux are radial and are therefore normal to each boundary surface. The flux density at any distance x from the axis is 55

$$\frac{\psi}{A} = \frac{\psi}{2\pi x}$$

where A is the area per unit length.

The elastance of a number of condensers in 60 series may be written

$$\frac{1}{C} = \frac{1}{C_1} + \frac{1}{C_2} + \frac{1}{C_3} + \dots \text{ etc.}$$

For concentric cylinders the capacitance per unit 65 length may be written

$$C_1 = \frac{\epsilon_1}{2 \log \frac{r_2}{r_1}}; C_2 = \frac{\epsilon_2}{2 \log \frac{r_3}{r_2}}; C_n = \frac{\epsilon_n}{2 \log \frac{r_{n+1}}{r_n}}$$

in which C_1 is the capacitance of a cylindrical tube having radii r_1 and r_2 and specific inductive capacitance ϵ_1 ; C_2 is the capacitance of a cylindrical tube having radii r_2 and r_3 and specific inductive capacitance ϵ_2 ; and C_n is the capacitance 70 75

of a cylindrical tube having radii r_n and r_{n+1} and specific inductive capacitance ϵ_n .

Hence, the total elastance of a series of concentric cylinders may be expressed as

$$5 \quad \frac{1}{C} = 2 \left\{ \frac{\log \frac{r_2}{r_1}}{\epsilon_1} + \cdots + \frac{\log \frac{r_{x+1}}{r_x}}{\epsilon_x} + \cdots + \frac{\log \frac{r_{n+1}}{r_n}}{\epsilon_n} \right\}$$

and

$$10 \quad C = \frac{1}{2 \left\{ \frac{\log \frac{r_2}{r_1}}{\epsilon_1} + \cdots + \frac{\log \frac{r_{x+1}}{r_x}}{\epsilon_x} + \cdots + \frac{\log \frac{r_{n+1}}{r_n}}{\epsilon_n} \right\}} \quad \begin{matrix} \text{centi-} \\ \text{meters} \\ \text{per cm.} \\ \text{of length} \end{matrix}$$

15 OR

$$C = \frac{5.55 \times 10^{-13}}{\frac{\log \frac{r_2}{r_1}}{\epsilon_1} + \cdots + \frac{\log \frac{r_{x+1}}{r_x}}{\epsilon_x} + \cdots + \frac{\log \frac{r_{n+1}}{r_n}}{\epsilon_n}} \quad \begin{matrix} \text{farads} \\ \text{per cm.} \\ \text{of length} \end{matrix}$$

20 If the inner cylinder is given a charge ψ per unit length, the electric intensity at a distance x from the axis is

$$25 \quad \frac{dV}{dx} = \frac{-2\psi}{\epsilon_x} = \frac{-2CE}{\epsilon_x}$$

and substituting this value in Equation 7, we obtain

$$30 \quad g_x = \frac{-E}{\epsilon_x x \left\{ \frac{\log \frac{r_2}{r_1}}{\epsilon_1} + \cdots + \frac{\log \frac{r_{x+1}}{r_x}}{\epsilon_x} + \cdots + \frac{\log \frac{r_{n+1}}{r_n}}{\epsilon_n} \right\}} \quad (9)$$

From the above it will be seen that mathematical expressions have been developed for the capacitance and gradient of an ignition cable having any desired number of dielectrics. These equations or expressions may now be graphically recorded, and in Fig. 2 of the drawing I illustrate such a graphical representation of the equations.

The curves of Fig. 2 are drawn for the simple case of a homogeneous dielectric as illustrated by Equations 3 and 6. This simplification in no way impairs the usefulness of the curves because the conclusions to be drawn could also be derived from graphs of the more general Equations 7 and 9. Furthermore, the simple Equations 3 and 6 very closely approximate the actual conditions because in general practice, the insulation of an ignition cable is largely made up of a single dielectric, namely a rubber compound.

50 The curve A, illustrated in Fig. 2 is the graphical representation of Equation 3 in which ϵ was assumed to be 3.5, which is the average value of ϵ obtained from a number of samples of ignition cable. The abscissae in this graph represent the ratio

$$\frac{r_1}{r_2}$$

60 that is, the ratio of the radius of the conductor to the radius of the cable. A second abscissa scale is shown, giving the conductor radius in centimeters when the cable radius is fixed at 0.38 cm. or an outside diameter of approximately three-fourths of a centimeter. The ordinates represent the capacitance per meter of the cable expressed in micro-microfarads. It is apparent from this curve that the capacitance increases from zero for zero radius of the conductor to infinity for a conductor radius equal to the outside radius of the cable. Practically, neither of these extremes is attainable.

The curve B, illustrated in Fig. 2 is the graphical representation of Equation 6. I have used a value for E of 15,000 volts and for r_2 of 0.38 cm. The value for E is the average maximum

voltage I have found necessary to fire the spark plugs found in internal combustion chambers of airplanes and the value for r_2 is the average outside radius of the ignition cable used with such spark plugs. The abscissae for curve B represent either the ratio

$$\frac{r_1}{r_2}$$

or r_1 in centimeters, and the ordinates represent the gradient at the surface of the conductor expressed in kilovolts per centimeter. It is apparent from this curve that the gradient at the surface of the conductor drops from infinity for a zero radius conductor to a minimum value of approximately 107 kv. per cm. for

$$\frac{r_1}{r_2} = \frac{1}{2.718}$$

to infinity again for

$$\frac{r_1}{r_2}$$

equal to unity. If a cable were designed only for minimum gradient in the dielectric the ratio of the radius of the conductor to the radius of the cable would be chosen for the minimum point of the curve B. If the insulation adjacent to the conductor will safely stand gradients in excess of this minimum value a decrease in capacitance may be obtained by decreasing the ratio

$$\frac{r_1}{r_2}$$

It is desired to obtain the maximum possible decrease in capacitance without subjecting the insulation to excessive electrical strains. If the term P is defined as the ratio of the capacitance for any value of the ratio

$$\frac{r_1}{r_2}$$

which may be denoted as R, to the capacitance when

$$45 \quad R = \frac{1}{2.718}$$

and the term Q is defined as the ratio of the gradient at the surface of the conductor for the same chosen value of R to the gradient at the surface of the conductor when

$$50 \quad R = \frac{1}{2.718}$$

then the product PQ will represent the relative decrease in capacitance obtained by a decrease of R multiplied by the relative increase in gradient which momentarily results when R is decreased. The product PQ has a minimum value when R is equal to

$$60 \quad \frac{1}{(2.718)^2} = 0.135$$

If the gradient corresponding to this value of R is in excess of the maximum safe gradient in the insulation adjacent the conductor, the outside radius of the conductor should be increased until the gradient when $R=0.135$ is equal to the maximum safe gradient. I have found that this is an essential requirement when the capacitance of the cable is of importance. If, however, the gradient when $R=0.135$ is less than the maximum safe gradient in the insulation adjacent to the conductor, a further decrease in capacitance may be obtained by decreasing R until the gradient in the insulation adjacent the conductor is equal to the maximum safe gradient in

75

the insulation. I have found that in any cable where capacitance is of importance, as in cables used in ignition systems of internal combustion engines, the outside radius of the cable should be so related to the maximum safe gradient in the insulation adjacent the conductor as to permit a value for R equal to or less than 0.135.

Another important factor to be considered in building an ignition cable is the gradient at the surface of the cable. This gradient may be effective in the formation of corona in the air at the surface of the cable, and the corona formation may have destructive effect on the rubber of the cable. The relationship between the gradient in the air space at the surface of the cable and the properties of the cable may be determined from a special form of Equation 9. This form is

$$gr_2 = \frac{E}{\epsilon_1 r_1 \left\{ \log \frac{r_1}{r_2} + \log \frac{r_3}{r_2} \right\}} \quad (10)$$

where r_1 is the radius of the conductor of the cable, r_2 the outside radius of the insulation, and r_3 the inside radius of the conducting shield.

The specific inductive capacitance of the cable is represented by ϵ_1 and of the air, ϵ_2 . This latter quantity may be considered as unity. Generally r_3 and r_2 are so nearly equal that their ratio may be considered as unity so that the expression for the gradient at the surface of the cable becomes

$$gr_2 = \frac{\epsilon_1 E}{r_2 \log \frac{r_1}{r_2}} \quad (11)$$

The curve C of Fig. 2 is the graph of this equation using values of E , ϵ_1 and r_2 of 15,000 volts, 3.5 and 0.38 centimeters, respectively. The abscissae and ordinates are the same as for curve B except that the ordinate scale is of different magnitude. It will be observed that the form of this curve is similar to the one for capacitance.

In most high voltage cable design, the choice of the diameter of the conductor is of first importance. This value is chosen with regard to the permissible resistance of the cable per unit length. I have found that the resistance of the conductor in an ignition cable is not an important factor, as regards its effectiveness in transferring energy from a spark coil or magneto to a spark plug, consequently no restrictions in design need be imposed by resistance considerations of the conductor.

In fact, I have found that from the standpoint of reduced radio interference and efficient spark plug operation, a high resistance is desirable. This point of view is opposite to that of present practice in ignition cable design. The upper limit to the resistance occurs when the time constant of the circuit becomes appreciable or the energy lost in the conductor becomes an appreciable part of total energy transferred. Using present known alloys or metals this upper resistance limit would not be reached unless the conductor diameter were reduced to a point far beyond the limit permitted by safe electrical gradient and mechanical strength. This means that in the development of an ignition cable of minimum capacitance according to the present invention no limitations as to conductor size or material will be imposed by resistance requirements.

I have therefore found that the ignition cable of minimum capacitance is the cable with the conductor of smallest diameter consistent with safe gradient in the dielectric and sufficient mechan-

ical strength. I have found from Equation 6 that the optimum ratio of the radius of the conductor of this wire to radius of the cable is given by the following equation

$$R^2 = e \frac{-E}{r_2 G} \quad (12)$$

Where

$$R = \frac{r_1}{r_2}$$

E is the magnitude of the highest voltage necessary to fire the spark plug, G is the magnitude of the maximum gradient the dielectric of the cable can stand without breakdown and r_2 is the outside radius of the cable. Practically, the value of R may be determined from curve B of Fig. 2. The value of R will be the abscissa of the point on the curve whose ordinate is equal to G . I have found that if rubber is used as the dielectric, having a value for G of about 240 kv. per cm. the values for R and r_1 are approximately 0.06 and 0.023 cm. respectively, or a conductor diameter of approximately one-half millimeter. I have found that a large number of the rubber insulating compounds of ignition cables now in use withstand gradients of this magnitude. I have also found that if a wire of this size be made of steel, stainless steel, phosphor bronze or other material of high tensile strength, its mechanical properties are satisfactory. I have also found that the use of such high tensile strength conductors instead of the customary copper offers additional advantages over copper because of their higher resistance. The higher resistance of the ignition cable reduces radio interference because of increased damping in the interfering waves and reduces the intensity of the current in the spark causing less wear on the spark plug electrodes.

The previous equations and curves refer to a cable with a solid conductor. In the practical application of the art stranded conductors are generally used in the construction of ignition cables. This departure will not materially affect the capacitance consideration but it will modify the gradient at the surface of the conductor. From a practical standpoint only the change in the gradient at the surface of the conductor need be considered when the change is made from a solid to a stranded conductor. This correction to the gradient equation may be adequately made by use of a constant K_n which represents the per cent increase in the gradient in the dielectric at the surface of the conductor when a change is made from a solid conductor to a stranded conductor of n strands and having the same total cross sectional area as the solid conductor. The value of K_n may be considered as a constant as regards both the range of ratio of radii of conductor to cable and the number of strands in a stranded cable which are of importance in ignition cable design. The equation which defines the desired ratio of conductor radius to cable radius may then be written

$$R^2 = e \frac{-E(1+K_n)}{r_2 G} \quad (13)$$

Values for K_n may be obtained from standard treatises on dielectric theory (see for example "Theory of Dielectrics" by Schwaeger and Samson, page 275). K_n is approximately the same for both 7 strand and 19 strand conductors and is about 30%. The optimum value of R may then be found by dividing G by $(1+K_n)$ and determining the abscissa for the point on curve B of Fig. 2 whose ordinate is $G/(1+K_n)$. The value of R will be the abscissa then selected. If a

value for G of 240 kilovolts per cm. is used, the value of $G/(1+K_n)$ is about 180 kilovolts per cm. and the abscissa corresponding to this ordinate is 0.086 such abscissa being chosen from a point 5 on the curve to the left of the minimum thereof. This corresponds to a radius for the conductor of 0.032 cm., or a diameter of approximately three-fifths millimeter.

A further advantage arising from this use of 10 the smaller conductor is that the gradient at the outside surface of the cable will be less, since as shown in curve C of Fig. 2, this gradient decreases as the diameter of the conductor decreases. Therefore the possibility of a detrimental effect on the rubber dielectric from corona 15 is less because of the use of this wire.

The definition of the optimum value for the ratio of the radius of conductor to radius of the cable will be modified further by the presence of 20 other dielectrics in the cable such as braid and lacquer as shown in Fig. 1. The general equation for the magnitude of the gradient at the surface of the conductor in the general case of a number of dielectrics may be obtained from Equation 9 25 and is

$$gr_1 = \frac{E(1+K_n)}{\epsilon_1 R r_{n+1} \left\{ \frac{\log \frac{r_2}{R r_{n+1}}}{\epsilon_1} + \frac{\log \frac{r_3}{r_2}}{\epsilon_2} + \cdots + \frac{\log \frac{r_{n+1}}{r_n}}{\epsilon_n} \right\}} \quad (14)$$

Where R is equal to

$$R = \frac{r_1}{r_{n+1}} \quad (15)$$

i. e., the ratio of the conductor radius to the outside radius of the cable.

The value of optimum radius in the general case will then be

$$(RM)^n = e^{-\frac{E(1+K_n)}{r_{n+1} G}} \quad (15)$$

Where M is a constant defined as follows

$$M = \frac{r_{n+1}}{r_1} \times \left(\frac{r_2}{r_3} \right)^{\frac{\epsilon_1}{\epsilon_2}} \times \left(\frac{r_3}{r_4} \right)^{\frac{\epsilon_2}{\epsilon_3}} \times \cdots \times \left(\frac{r_n}{r_{n+1}} \right)^{\frac{\epsilon_{n-1}}{\epsilon_n}} \quad (16)$$

The particular conductor sizes set forth hereinbefore are entirely practicable when a good insulating material is employed and when it is not necessary to take into consideration thermal conditions under which the ignition cable may be used. Where, however, the ignition cable is used under high temperature conditions, the primary 55 consideration is the provision of a heat resistant insulating compound, and it has been found that insulating compounds having good thermal properties do not, usually, have good electrical properties. Consequently, if an insulator having good thermal properties and poorer electrical 60 properties must be used, it becomes necessary to reduce the maximum allowable gradient at the surface of the conductor, in order to prevent failure of the cable. In order to bring the 65 gradient within allowable limits the radius of the conductor may be increased, and I have found that a conductor made up of seven strands of stainless steel wire, each strand having a diameter of approximately .013 inch, provides satisfactory results under the conditions set forth. 70 Such a stranded conductor has a diameter of approximately .039 inch (approximately .99 millimeter) or a diameter of approximately one milli-

meter. The corresponding solid conductor has a diameter of approximately .0172 inch (approximately .872 millimeter) or a diameter of approximately seven-eighths of a millimeter. In neither case need the outside radius of the cable be 5 changed.

The conductor dimension values given hereinbefore in the several cases are not the only conductor or cable radii which fall within the scope of the invention, and such values of conductor and cable radius are to be construed as illustrative of constructions coming within the broad scope of the invention, and as illustrating the fundamental theory on which the invention is predicated, namely that the capacitance of the cable is to be made as small as possible, and the resistance is to be increased, all without increasing the electrical gradient above allowable limits and without decreasing the mechanical strength of the cable below allowable limits.

It will be apparent to those skilled in the art that while I have disclosed my invention with particular reference to an ignition cable construction, the invention is not limited to the field of ignition cables, but may be employed in designing and constructing an electrical conductor for use under any conditions where low capacitance or high resistance of the conductor is to be achieved. Obviously, cables constructed according to my invention may be employed for any electrical use without departing from the spirit or scope of the invention, and the invention is not to be considered as being limited to ignition cable construction.

It is to be expressly understood that the present invention is not limited to any specific modification disclosed herein, or otherwise than by the appended claims.

The invention described herein may be manufactured and used by or for the Government of the United States of America for governmental purposes without the payment of any royalties thereon or therefor.

I claim:

1. An electrical cable comprising a conductor and insulating means surrounding the conductor, the diameter of the conductor being so related to the outside diameter of the cable that the relationship $PQ \approx 0.135$ is obtained, in which P is the ratio of the capacitance of the cable to the capacitance when the ratio of the radius of the conductor to the radius of the cable is

$$\frac{1}{2.718}$$

and Q is the ratio of the gradient at the surface of the conductor of the cable to the gradient at the surface of the conductor when the ratio of the radius of the conductor to the radius of the cable is

$$\frac{1}{2.718}$$

2. An electrical cable comprising a conductor and dielectric means surrounding the conductor, the cable being so constructed that the ratio of the radius of the conductor, r_1 , to the radius of the dielectric means, r_2 , is equal to

$$\frac{r_1}{r_2} = \frac{1}{e^3}$$

in which e is the natural logarithmic base.

MELVILLE F. PETERS.
